HEATING MEANS FOR MINERAL OILS.

1,173,107.

Specification of Letters Patent.

Patented Feb. 22, 1916.

Application filed April 21, 1915. Serial No. 22,913.

To all whom it may concern:

Be it known that I, CLARENCE E. GRAVES, a citizen of the United States, residing at Wellsville, in the county of Allegany and

5 State of New York, have invented certain new and useful Improvements in Heating Means for Mineral Oils, of which the following is a specification, reference being had to the accompanying drawings.

10 In the handling of crude petroleum as delivered from the wells, for marketing the same, it is customary to store temporarily the oil as pumped or flowed from the several wells on a given oil property, or "lease," in 15 a tank of a size sufficient to hold the production for some little period, and then at intervals as the tank becomes filled or nearly so to have the tank "run" into the main or trunk oil lines by the gager. Such temporary storage tanks on the individual oil properties are of varying sizes according to 20 the products of the respective "leases," being however ordinarily of a capacity of fifty barrels or upward.

25 Since it is a well known property of crude petroleum to thicken so as to be only semi-fluid when chilled, it is necessary to heat the oil contents of these temporary storage tanks in colder weather so as to render the 30 oil sufficiently fluid to be readily "run" into the trunk pipe lines. For this purpose it has been customary to steam the filled tanks by passing steam through pipes in said tanks until the oil is heated to the requisite degree. This has been a relatively expensive and troublesome method requiring considerable piping from a more or less distant source of steam supply, for which also of course provision had to be made in the form 35

40 of a suitable pressure boiler. This "steaming" of the tanks has hitherto been the only resort for the purpose of heating the tanks for the reason that it has not been considered practicable to associate a combustion burner 45 or combustion chamber directly with the oil storage tanks because as the contents of the tanks become heated the more volatile portions of the crude petroleum, *i. e.*, the naphtha, gasoline, etc., with a low flashing point are given off in considerable quantity 50 from the surface of the oil in the tank, creating a danger area where combustion or explosion is very likely or certain to occur when there is any highly heated flue for the 55 products of combustion, or free fumes of the

products of combustion, in the neighborhood of this danger zone thus charged with inflammable gases.

The prime object of the present invention is to provide means whereby a combustion burner or chamber may be associated directly with a temporary storage tank for crude petroleum or the like and having flues for the conveyance of the products of combustion extending through the body of the oil in the tank, preferably in a circuitous path, in a manner so that most of the heat produced is delivered to the body of the oil for heating the same and at the same time, said flues and the combustion chamber and burner being so arranged that when the tank is full or well filled with oil, there is no portion of said flues exposed in the danger zone above the surface of the oil, nor any possibility of discharge of the products of combustion in proximity to such danger zone, thus doing away with possibility of explosion or combustion by the igniting of the gases produced and given off from the top surface of the oil where they are of course mixed with the atmospheric air to produce a highly inflammable mixture.

The invention will be better understood from the following detailed description taken in connection with the accompanying drawings and will be thereafter pointed out in the appended claims.

Referring to the drawings: The view presented shows partly in elevation and partly in section an oil storage tank equipped with a combustion chamber and burner with flues leading therefrom through the lower part of the tank only in accordance with my invention.

In the drawings a temporary storage tank for crude petroleum or the like is indicated at 1 of any desired capacity, usually of from fifty to one hundred fifty barrels. An inlet pipe 2 is shown as delivering into the top of this tank, there being in practice one or more of these pipes discharging from the several wells on the oil property. A discharge pipe is indicated at 3 leading from the bottom of the tank to a trunk pipe line or other point of discharge.

Leading up from the bottom of the tank 1 and as shown, toward one side thereof, is an upwardly disposed flue 4 shown as of tubular form in communication at its lower end and through the bottom of the tank with a

2 combustion chamber C, herein shown as constituted by a shallow trench underneath the main central portion of the tank with a banking around the periphery of the tank to inclose the same, this trench being usually produced in the earth on which the tank is set. The flue 4 extends upwardly to a point as shown somewhat below the vertical center of the tank and always well below the top 5 of the tank and has as shown a horizontal continuation 5 extending out through the side of the tank where it is led off to a remote discharge point by an upward flue extension 6, preferably having a suitable damper 7 interposed therein. It will be understood that the vertical flue portion 4 and the horizontal flue portion 5 are in a broader sense merely illustrative and intended to typify any suitable flue path, preferably circuitous, leading from the combustion chamber C through the body of the oil in the lower portion of the tank and so arranged as to be entirely in the lower portion thereof, and passing outward from the tank to a 10 relatively remote point without having any portion exposed within the upper portion of the tank so as to be liable to cause ignition of the volatile fumes given off from the surface of the oil. The flue portions 4, 5 may be of any suitable diameter according to the size of the tank and of the combustion chamber employed, though a diameter of about six inches is generally best adapted for the purpose. The outward flue extension 6 may be of a somewhat smaller diameter than the flue portions 4, 5 and in conjunction with the damper 7 when this is used, may retard the passage of the products of combustion through the flues 4, 5 to a 15 determined extent so as to obtain the maximum heating effect therefrom while still creating the requisite draft from the combustion chamber. In practice the outer upward extension or stack portion 6 of the flue, will extend up to a substantial distance above the top of the tank as well as at one side thereof so that any danger of ignition from the products of combustion as given off therefrom is eliminated. 20

50 Any suitable heating medium may be employed in the combustion chamber C but as shown, and preferably when practicable, I employ a hydro-carbon burner 8 either discharging natural gas or a spray of oil under pressure, into the combustion chamber, preferably at one end thereof and adjacent the side of the tank 1 opposite the opening of the flue 4 so that the major portion of the base of the tank will be subjected primarily 25 to the heating medium. Then as the products of combustion pass up through the flues 4, 5 still more of the heat thereof is of course given off into the body of the oil in the tank which is thereby heated to the 30 requisite extent in a relatively short time

with a maximum conservation of the heat employed, it being noted that the only path of escape for the products of combustion as discharged from the flame of the burner 8 is across the bottom of the tank and thence 70 through the relatively large and circuitous flue passages 4, 5. It will of course be understood that this heating means is employed only preparatory to the "running" of the tank contents, *i. e.*, when the tank is 75 filled or nearly so, and that the burner 8 will be turned off so that the flues 4, 5 and the bottom of the tank will cool as the level of the oil in the tank lowers and thus before the top of the flue 5 is uncovered, its temperature will be low enough so that there is no danger of ignition of the gases from this source. Thus it will be understood while the burner 8 is in operation the flues 4, 5, and the bottom of the tank subject to impingement by the products of combustion are kept relatively cool by contact with the body of the oil being heated and this fact in connection with the further fact that the free gaseous products, *i. e.*, the naphtha, etc., 80 are only liberated and mixed with air above the top of the oil in the tank insures against danger of ignition or explosion in the practice of my invention since by no possibility can any of the products of combustion or 85 any heated flue portion be exposed above the surface of the oil in the tank while it is being heated, only requiring of course that the tank shall be fairly well filled as is always the case in practice before it is run by the 90 gager. Thus as shown the tank is only about two-thirds full of oil but the surface thereof is still considerably above the top of the flue 5. In practice the top of the tank 1 will also usually be covered with a tight cover, 105 thus further insuring against the mingling of any hot products of combustion with the gases freed from the surface of the oil.

I do not desire to be limited to the precise structural details herein exhibited since 110 these may be embodied in other specific forms without departing from the spirit or essential attributes of the invention, and I therefore desire the present embodiment to be considered as illustrative and not restrictive, reference being had to the appended claims rather than to the foregoing description to indicate the scope of the invention.

Having now described my invention, what 120 I claim as new and desire to secure by Letters Patent is:

1. A storage tank for crude petroleum or the like, having a combustion chamber associated therewith, and a delivery flue from 125 said combustion chamber leading in a circuitous path through the lower portion only of the interior of said tank, and with a delivery connection to a relatively remote point without the tank, all portions of said 130

flue within the tank being below the normal level of the oil therein to be heated thereby.

2. A storage tank for crude petroleum and the like, having a combustion chamber thereunder arranged for the products of combustion to impinge on the bottom of the tank, and a flue leading upward from said chamber within the tank and passing in a circuitous path through the lower portion 10 only of said tank, and discharging therefrom laterally at a relatively low point therein with a delivery connection to a remote point, said combustion chamber and flue being so arranged that exposure of the 15 products of combustion or of any heated flue portion in the danger zone above the normal surface of the oil in said tank is prevented.

3. A storage tank for crude petroleum or 20 the like, having an inlet pipe at its top and a discharge pipe at its bottom, a combustion chamber associated with the lower portion of said tank and having a combustion burner arranged to direct products of combustion 25 against an area of the outer surface of said tank, a flue leading in a circuitous path from said combustion chamber upward into said tank and outward laterally therefrom and continued entirely in the lower portion of 30 said tank, and an outer stack extension of said flue leading upward to a relatively remote point.

4. A storage tank for crude petroleum or the like, having an inlet pipe at its top and 35 a discharge pipe at its bottom, a combustion chamber associated with the lower por-

tion of said tank and having a combustion burner arranged to direct products of combustion against an area of the outer surface of said tank, a flue leading in a circuitous 40 path from said combustion chamber upward into said tank and outward laterally therefrom and contained entirely in the lower portion of said tank, an outer stack extension of said flue leading upward to a relatively remote point, and a damper for controlling the draft created by said stack extension. 45

5. A storage tank for crude petroleum or the like, having an inlet pipe at its top and 50 a discharge pipe at its bottom, a relatively shallow combustion chamber formed underneath the major portion of said tank, a combustion burner at one end of said chamber and adjacent one side of said tank, a flue 55 extending upward within the tank from said combustion chamber adjacent the other end thereof and at the other side of said tank, a horizontally extending continuation of said flue leading laterally outward of said tank and contained entirely in the lower portion thereof, and an upward stack extension for said flue at the outside of the tank for delivering the products of combustion at a relatively remote point. 60

In testimony whereof I hereunto affix my signature in the presence of two witnesses.

CLARENCE E. GRAVES.
